Specification for Design.

Patented Aug. 10, 1920.

Application filed March 29, 1920. Serial No. 369,754. Term of patent 7 years.

To all whom it may concern:

Be it known that I, WESLEY W. KUHLMANN, a citizen of the United States, residing at Woodcliff-on-Hudson, (Guttenberg post office), in the county of Hudson and State of New Jersey, have invented a new, original, and ornamental Design for an Automobilist's Hand-Signal, of which the following is a specification, reference being

had to the accompanying drawing, forming part thereof.

The figure is a plan view of an automobilist's hand signal showing my new design.

I claim:

The ornamental design for an automobilist's hand signal.

WESLEY W. KUHLMANN.
